UNITED STATES PATENT OFFICE.

RICHARD MONTGOMERY, OF NEW YORK, N. Y.

IMPROVED SHIELD FOR IRON-CLAD VESSELS.

Specification forming part of Letters Patent No. 35,495, dated June 3, 1862.

To all whom it may concern:

Be it known that I, RICHARD MONTGOMERY, of the city and State of New York, have invented a new and useful improvement upon an invention patented to me on the 18th day of March, 1862, entitled "Improved Iron-Clad Vessels;" and I do hereby declare that the following is a full, clear, and exact description of the construction and operation of the same, reference being had to the annexed drawings, making a part of this specification, in which—

Figure 1 represents a front and Fig. 2 a side view thereof.

The object of this invention is to place a shield over the orifices shown in the sides of my improved iron-clad vessels and give additional protection to the flaring surfaces of the said orifices shown in that invention.

In Fig. 1 two of these shields are shown; but as one is to be placed over each orifice, the number in a ship's sides will be determined by the number of these orifices she may have.

a shows this shield in its normal position, and *b* the shield thrown around upon its axis, exposing a portion of the orifice of the hollow tube or conductors described in the patent above referred to. This shield is of an irregular form, its two exterior faces consisting each of a truncated triangle, with their faces inclined to each other in such a manner that they meet at the line of the axis of motion. The deflection of these faces from each other is such as to make the edges of the shield, when in its normal position, meet the flaring sides, or nearly so, of the orifices in the sides of the ship, thus closing more or less these orifices and completely covering the openings into the hollow tubes or conductors. The surfaces of the shield may be plain or corrugated, and the material used may be wrought or cast iron or steel. I propose, therefore, either to cast the shield entire in a solid mass or to make it of heavy plate iron or steel, in the latter case filling the cavity, if any, with wood, sand, or water, or leaving it empty.

This shield moves on an axis of iron or steel of sufficient strength and size attached or formed at the junction of the base of the two exposed faces of the shield. This axis I prefer to make vertical, or nearly so, and so arranged in its bearings upon inclined surfaces

or otherwise as to cause the shield to return by its own gravity to its normal position after having been displaced by a projectile or other cause; or, by a proper application of some appropriate mechanical device, the axis might be placed horizontally. This axis stands out, as seen in Fig. 2, some distance above or beyond a plane that would be formed by the edges of the flaring orifices of the conductors *o*, the effect of which arrangement is to protect in a great measure the flaring sides of the conductor from the effect of projectiles when discharged, so that they would otherwise strike these surfaces at or near a right angle. The axis is supported, as shown at *c c*, by a beam or knee bent at a proper angle and secured properly to the sides of the vessel. *d d* show the ends of the axis passing through this knee or beam.

The operation of the shield is very evident from the description of its construction. If a cannon-ball or other projectile were discharged in the direction shown by the arrow *x*, so that its line of flight should be perpendicular, or nearly so, to the plane of the flaring face *y* of the orifice *o*, it would, if it met with no obstruction, penetrate this face if the cohesion and momentum of the projectile were sufficient to overcome the resistance of the face, inasmuch as, striking the latter with this direction, there would be little or no tendency to glance; but a very slight deflection from this direction would produce this tendency. If, therefore, before reaching this face, the projectile should come in contact with a yielding body of considerable inertia arranged as the face *z* of the shield, a new direction would be impressed upon it, (the projectile,) and this might be sufficient to make it pass at once into the conductor, whose orifice would be exposed by the rotation of the yielding shield, or at least cause it to strike the surface *y* at such an angle as to cause it to glance therefrom into the same orifice.

What I claim is—

A shield arranged and operating substantially in the manner set forth.

RICHARD MONTGOMERY.
